UNITED STATES PATENT OFFICE.

JOSEPH B. BROLASKI, OF ST. LOUIS, MISSOURI.

WATER-TIGHT COMPARTMENT FOR VESSELS.

SPECIFICATION forming part of Letters Patent No. 451,803, dated May 5, 1891.

Application filed June 17, 1890. Serial No. 355,707. (No model.)

To all whom it may concern:

Be it known that I, JOSEPH B. BROLASKI, of St. Louis, in the State of Missouri, have invented a new and Improved Construction of 5 Water-Tight Compartments for Vessels, of which the following is a full, clear, and exact description.

My invention relates to improvements in the construction of water-tight compartments 10 for vessels; and the object of my invention is to provide means for constructing an inexpensive yet substantial water-tight compartment having suitable openings, which when closed will protect the boat from sinking 15 should it spring a leak, and when open will permit of the ready hauling of the cargo and not interfere with its safe stowage.

To this end my invention consists in certain 20 features of construction and combinations of parts, which will be hereinafter described and claimed.

Reference is to be had to the accompanying 25 drawings, forming a part of this specification, in which similar letters of reference indicate corresponding parts in all the figures.

Figure 1 is a broken perspective view showing the inside of a compartment constructed in accordance with my invention. Fig. 2 is a sectional plan showing the construction and 30 arrangement of the bulk-head or partition forming one side of the compartment. Fig. 3 is a broken detail perspective view showing the relative arrangement of the compartment-doors and skidway; and Fig. 4 is a 35 broken detail sectional view showing a bulk-head door partially open and the adjacent bulk-head to brace it.

In the accompanying drawings, A represents the inside of a vessel's hull; B, vertical ribs 40 of the same, and B' some of the vessel's knees. The timbers C, which may be the bottom timbers, extend transversely across the vessel's hull, and attached to the under side of the said timbers, so as to form the outside planking 45 of the hull, are the strips c. The vessel is also provided with a suitable deck D, supported upon the deck-timbers d, and has a suitable hatch D', by means of which access may be had to the compartment. The 50 vertical partition or bulk-head E, which forms a side of the compartment, extends transversely across the vessel, being formed of

matched boards, as shown in the drawings, although it may be formed of metal, if desired. The bulk-head E is held in position 55 by the vertical posts E', which are arranged upon each side of the bulk-head and extend from the bottom timbers C to the deck-timbers d, the bulk-head being firmly secured to the said bottom timbers C. The bulk-head E 60 and the posts E' are securely fastened to the bottom timbers C, and are re-enforced by the cleats e, which are attached to the timbers so as to bear against the posts. At the top the bulk-head and posts are held in place by similar 65 cleats which are attached to the deck-timbers d. The bulk-head and posts are not spiked to the deck-timbers, and the cleats will permit the necessary twist or racking movement caused by uneven loading, waves, &c. 70

Opening through the side of the bulk-head E are the double doors H, which are formed of double boarding laid diagonally in opposite directions, so that each strip of boarding will serve as a brace to the doors. The doors are 75 hinged to the bulk-head E, and are provided with vertical bolts h, having suitable handles h', by which they may be operated, said bolts projecting into suitable sockets in the timbers C at the bottoms of the doors and connecting with suitable bolts h², which extend into sockets in the timber d at the tops of the doors. The doors are provided with these bolts upon the outer and inner sides, so that they may be securely locked; and while I 85 have shown and described a peculiar form of bolt any suitable bolt may be substituted.

The inner edges of the doors are doubly beveled, as shown, to enable them to fit between the bulk-heads E and I, as hereinafter 90 described, and the outer edge of one door is provided with a beveled portion h³, which fits in the corresponding groove h⁴ of the opposite door. The doors are also slightly beveled at top and bottom, so that when they are 95 closed in position they will form a water-tight joint.

Opposite the inner edge of each door H is a vertical narrow bulk-head or partition I, said bulk-heads being parallel with the bulk-head E, and the bulk-heads I are secured to the bulk-head E by suitable bolts, a spacing-strip i being inserted between the bulk-heads I and E to hold them the necessary distance 100

apart, and a suitable support i' being placed against the bulk-heads I and E for the ends of the bolts to give additional strength to the connected parts. It will thus be seen that 5 when the doors H are closed the inner beveled edges of the same will fit closely between the bulk-heads I and E, forming thereby a water-tight joint.

10 A skidway to facilitate the easy handling of the cargo extends across the timbers C, opposite the doors H, said skidway being formed of the parallel timbers J. The skidway is also provided with a hinged section formed of the timbers J', so that when the doors H are 15 closed the timbers J' may be dropped against the doors, and will thus securely brace them, so that they may resist the pressure of water when necessary. From the foregoing description it will be seen that the compartments 20 may be filled with cargo, if necessary or desirable, and that by means of the doors H and the skidway the cargo may be readily shifted from one compartment to another.

Each compartment may be provided with 25 a pump tube or box with holes at intervals therein to allow any water which may be in the hold to enter freely into the tube or box, and a suitable tell-tale may be inserted in the tube and connected with an alarm near the 30 engineer's stand, so as to notify him when the water rises in the tube, whereby a leak, if any, may be located, the extent of the leak determined, and it can be ascertained whether the leak is confined to one compartment or 35 extends to others.

By a system of pipes and cut-off valves the pumps can be applied to any one or all of the

compartments. The pipes may also be used in the event of fire in the hold and any compartment being filled with steam or with water without damaging other portions of the cargo. The usual scuppers or passages for bilge-water should be securely closed under each compartment. 40

Having thus fully described my invention, 45 I claim as new and desire to secure by Letters Patent—

1. In a water-tight compartment, the combination, with the bottom timbers and the deck-timbers d, supporting the deck D, having a suitable hatch D' therein, of the bulk-head E, extending vertically from the timbers C to the timbers d, the posts E', arranged upon each side of the bulk-head E and having cleats e for attachment to the timbers C 55 and d, the bulk-heads I, bolted to the bulk-head E and arranged parallel therewith, the intervening spacing-strip i, and the doors H, provided with suitable locking-bolts and having their inner edges beveled to fit between 60 the bulk-heads E and I and having interlocking outer edges and their upper and lower ends beveled, substantially as described.

2. In a water-tight compartment, the combination, with the door hinged in the bulk-head, as shown, of a skidway resting on the bottom timbers of the compartment and provided with a hinged section adapted to be closed upon the doors and serve as a brace, substantially as described. 65
